Filed April 17, 1941

UNITED STATES PATENT OFFICE

2,307,538

VACUUM CLEANER

George R. Paulus, Cleveland Heights, Ohio, assignor to Electric Vacuum Cleaner Company, Inc., Cleveland, Ohio, a corporation of New York

Application April 17, 1941, Serial No. 389,031

3 Claims. (CL. 248—15)

The present invention relates to tank type vacuum cleaners.

The object of my invention is to provide an improved construction and arrangement for resiliently supporting the motor, and for a consideration of what I believe novel and my invention, attention is directed to the following description and the claims appended thereto.

In the accompanying drawing, Fig. 1 is a sectional elevation of a vacuum cleaner embodying my invention; Fig. 2 is an end elevation, partly broken away, of the resilient supporting ring; and Fig. 3 is an end elevation of the motor and frame which cooperates with the supporting ring.

Referring to the drawing, there is shown a tank type vacuum cleaner having a cylindrical casing or tank 1 provided with end caps 2 and 3 respectively having an inlet opening 4 and an outlet opening 5. The inlet end cap 2 is releasably fastened to the casing by a plurality of latches 6 only one of which is shown. Within the inlet end of the casing is a bag 7 supported by a frame 8 including a ring 9 having an outwardly extending flange 10 covered with gasket material 11 and clamped between the casing and the inlet end cap 2. The bag has a reentrant portion 12 which during the operation of the cleaner is drawn against a post 13 extending from a perforated inlet 14 of the fan chamber toward the inlet opening 4. The reentrant portion 12 increases the filtering area of the bag. The fan chamber comprises a cup-shaped member 15, carrying the perforated inlet 14, which is telescoped over the end of a cup-shaped member 16. Within the fan chamber are centrifugal fans 17 and 18 fixed to a shaft 19. The air discharged from the fan 17 flows to the fan 18 through straightening vanes 20 fixed to the outer end of the cup-shaped member 16. The shaft 19 is rotated by an electric motor comprising a rotating element 21 mounted on the shaft 19 and a stationary element 22 carried in a frame comprising circumferentially spaced axially extending arms 23 connected at one end to a ring 24 carrying a bearing housing 25 for the shaft 19 and connected at the other end to a flange 26 presented to an end frame 27. The end frame 27 carries radially extending straightening vanes 28 having projections 29 seated in complementary depressions in the flange 26. The end frame 27 is secured to the flange 26 by screws 30 threaded into bosses 31 on the straightening vanes 28.

The motor and fan are resiliently supported by a ring 32 of rubber or similar resilient material having its inner part clamped between the flange 55

28 and a ring 33 resting on the bosses 31. The ring 33 cooperates with the vanes 28 to provide passages for receiving the discharge of the fan 18 and directing the same over the motor through 5 passages 34 at the inner ends of the vanes. The outer edge of the ring 32 is in sealing engagement with the inner surface of the cup-shaped member 16 so that all of the air discharged from the fan 18 flows over the motor. The air is kept 10 close to the motor so as more effectively to cool the same by a ring 35 clamped between the casing 1 and the outlet end cap 3 and providing a relatively restricted annular passage 36 around the motor. The outer part of the supporting ring 32 is fixed to the cup-shaped member 16 by screws 37 threaded into sockets 38 provided by tabs 39 struck out of a metal ring 40 and embedded in the supporting ring 32. The metal ring 40 is molded into the supporting ring 32. In the manufacture of the supporting ring 32, the metal ring 40 is placed in a mold having locating pins extending through openings 41 in the metal ring. The locating pins have the shape indicated at 15 the top of Fig. 1 in which the molded recess 42 corresponds to the part of the locating pin projecting through the opening 41, and the molded recess 43 corresponds to the part of the locating pin on which the metal ring 40 rests. The rubber ring has molded holes 44 for the bolts 30 and molded notches 45 which facilitate the assembly of the rubber ring into the cup-shaped member 16.

The above described construction for resiliently supporting the motor and the fans 17 and 18 facilitates manufacture and assembly. The ring 32 is first assembled on the motor which is then slipped into the cup-shaped member 16 of the fan casing and fastened therein by screws 37. After completing the assembly of the fan casing, 20 the motor and fan casing are inserted in a unit into the outer casing 1 and suitably fastened therein for example by screws 46.

What I claim as new and desire to secure by Letters Patent of the United States is:

- 45 1. In a vacuum cleaner, a casing, a motor fan unit therein, a ring of resilient material within said casing and surrounding said unit, means securing the inner part of said ring to said unit, a metal ring embedded in the outer part of the resilient ring and having sockets presented toward the casing, and fastening elements extending from the casing into cooperation with said sockets for securing the outer part of the ring to the casing.
- 50 2. In a vacuum cleaner, a casing, a motor fan unit therein, a ring of resilient material within

said casing and surrounding said unit, means securing the inner part of said ring to said unit, a metal ring embedded in the outer part of the resilient ring, tabs struck out of said metal ring transverse of its plane to define sockets presented toward the casing, and fastening elements extending from the casing into cooperation with said sockets for securing the outer part of the ring to the casing.

3. In a vacuum cleaner, a casing, a motor fan 10

unit therein, a ring of resilient material within said casing and surrounding said unit, means securing the inner part of said ring to said unit, a radially extending metal plate embedded in the outer part of the ring, a tab struck out of said plate to define a socket presented toward the casing, and a fastening element extending from the casing into cooperation with said socket for securing the outer part of the ring to the casing.

GEORGE R. PAULUS.
